(57) **CLAIM**

The ornamental design for a speedometer display, as shown and described.

DESCRIPTION

FIG. 1 is a front elevation view of a speedometer display showing my new design;

FIG. 2 is a view thereof showing several dynamic elements of the display;

FIG. 3 is a view thereof showing various dynamic elements in dashed lines;

FIG. 4 is a view thereof showing the dynamic elements of FIG. 3 in solid lines;

FIG. 5 is a view thereof showing various dynamic elements in a changed display;

FIG. 6 is a view thereof showing various dynamic elements in a further changed display;

FIG. 7 is a view thereof showing various dynamic elements in yet a further changed display;

FIG. 8 is a view thereof showing various dynamic elements in again a further changed display;

FIG. 9 is a view thereof with various dynamic elements assuming further display changes;

FIG. 10 is a view thereof with various dynamic elements assuming yet further display changes;

FIG. 11 is a view thereof with various dynamic elements assuming again further display changes;

FIG. 12 is a view thereof with various dynamic elements assuming additional display changes; and,

FIG. 13 is a view thereof with various dynamic elements, showing several further display changes.

The broken line showing of structural features is included for the purpose of illustrating non-claimed subject matter and forms no part of the claimed design.
